UNITED STATES PATENT OFFICE.

ANDREW W. SMITH, OF DES MOINES, IOWA.

TOILET-POWDER APPLICATOR.

Application filed July 16, 1927. Serial No. 206,291.

The principal object of this invention is to provide a toilet powder applicator that will hold and apply the powder to the body desired to be coated without loss of the powder.

5 More specifically, the object of this invention is to provide a toilet powder applicator comprising a reservoir for holding the powder and an opening in the reservoir covered with suitable porous material for yieldingly 10 retaining the powder in the reservoir and to also act as a powder puff.

A still further object is to provide a toilet powder applicator for holding and applying toilet powder that gives an even coating of 15 powder over the part treated.

A still further object is to provide a toilet powder applicator that may be easily and quickly attached to and detached from the hand of the user.

20 A still further object is to provide a toilet powder applicator and container that may be easily refilled with powder.

A still further object is to provide a toilet powder applicator that is durable and economical in manufacture and artistic in design.

These and other objects will be apparent to those skilled in the art.

My invention consists in the construction, 30 arrangement and combination of the various parts of the device, whereby the objects contemplated are attained as hereinafter more fully set forth, pointed out in my claims and illustrated in the accompanying drawing, in 35 which:

Fig. 1 is a perspective view of one of the forms of my toilet powder applicator having an adjustable handle secured thereto.

40 Fig. 2 is a side sectional view of the same toilet powder applicator taken on line 2—2 of Fig. 1 and more fully illustrates its construction.

Fig. 3 is another form of my toilet powder applicator having a fixed handle member which when removed, provides an opening for refilling the applicator.

45 Fig. 4 is a side sectional view of the powder applicator shown in Fig. 3 and is taken on line 4—4 of the same.

50 Fig. 5 is a side sectional view of a still different form of my toilet powder applicator

and is particularly adapted for the use of barbers.

Fig. 6 is a perspective view of still a different form of my toilet powder applicator 55 especially designed for applying powder to the body after bathing.

Fig. 7 is a side sectional view of the toilet powder applicator illustrated in Fig. 6 and is 60 taken on line 7—7 of the same.

Personal hygiene demands the frequent application of toilet powder to the face and especially to the body after bathing. To successfully coat the body with powder is somewhat of a task with the small powder puffs now on the market. Much powder is wasted and the puff must be repeatedly dipped in an open container having powder therein, during the process. The obtaining of an even coating is impossible. In applying powder 70 to the face, even a greater state of untidiness is experienced, as the puff and container must be carried loosely in the purse. I have overcome all these objections as will be appreciated by those familiar with the art.

In Figs. 1 and 2, I have designated the body portion of my powder applicator by the numeral 10 having the metal back 11. In the face of the member 10 and near its center is the opening 12, designed to hold the toilet 80 powder 13. Secured by any suitable means over this opening 12 and the face of the member 10 is the cloth 14 which may be of pile fabric or any suitable material adapted to the applying of face powder. By this construction, when the cloth 14 is agitated by the act of drawing the same over the part of the body to be powdered, the powder 13 will pass from the opening 12 through the cloth 14 and onto the skin in a very even coating. This cloth 85

14 will be continuously impregnated with the powder as long as any remains in the container, but unless the cloth 14 which acts as a powder puff, is agitated, the powder 13 will be yieldingly retained in the opening 12. 90 Mounted in the back of the member 10 and having its bottom open and communicating with the opening 12 is a small rouge box 15 having the hinged lid 16. In the bottom of this rouge box and closing the opening 12 is 100 a disk 17 of any suitable material. Resting on this disk is the rouge cake 18. The nu-

meral 19 designates a small rouge powder puff loosely placed in the rouge box. To facilitate the opening of the hinged cover 16, I have provided the small handle member 20. When it is desired to fill the opening 12 with a supply of powder, it is merely necessary to remove the rouge cake 18 and the disk 17. In order to make the applying of powder a dainty and easy task, I have provided a handle member. This handle member has three arms 21, each having one of their ends secured to a metal back 11 by suitable means and their other ends permanently secured to a rod 21' having the slot 22. Slidably mounted on this rod 22 is the grip portion 23 having the rivet 24 passing through the slot 22. By this arrangement, the handle may be adjusted to various lengths.

In Figs. 3 and 4, I have designated the body portion of my device by the numeral 25 having its peripheral edge extending forwardly as shown in Fig. 4. Around the forward face of this body portion 25 is the cloth fabric 26 designed to act as a powder puff and to yieldingly hold the powder 13 in the cup portion of the member 25. Threaded into an opening in the member 25 is the handle member 27. By this construction, when it is desired to place a new supply of powder in the applicator, it is merely necessary to remove the handle 27.

In Fig. 5 I have designated the body portion of my device by the numeral 28 having the reservoir 29 for the holding of face powder 13. On the forward end of the body member 28 extend a plurality of bristles 30. Threaded onto the rear end of the body member 28 is the handle member 31. To fill the reservoir 29 with toilet powder it is merely necessary to unscrew the handle 31 from the body portion 28. In order that the powder may pass from the reservoir 29 into the bristles 30 when the same are agitated, I have provided a plurality of small holes 32 adjacent the secured ends of the bristles.

In Figs. 6 and 7, I have designated the elongated body portion of my device by the numeral 33, which may be of wood or other suitable material and having the hole 34 near its center. The numeral 35 designates a forwardly extending peripheral edge on the face of the body portion to form a cup portion as shown in Fig. 7. Extending over the face of the body member 33 and secured to its periphery, is the powder puff 36. Entering and closing and frictionally engaging the side wall of the hole 34 is the cover member 37 having the handle member 38 secured thereto to facilitate its removal for the placement of toilet powder 13 in the hole 34. By this arrangement, the powder 13 may easily pass from the hole 34 to a position between the face of the body member 33 and the powder puff as shown in Fig. 7, where it will easily and evenly pass through the powder puff

when the same is agitated by use. In this construction it should be noted that the face of the body member adjacent the opening 34 acts as a supporting member back of the puff, thereby holding it in normal position at all times. The form of the toilet powder applicator shown in Figs. 6 and 7, is especially adapted to the applying of toilet powder after bathing and for this reason is comparatively large. In order that it may be easily operated, I have provided the straps 39 secured to the body 33 in any suitable manner, designed to receive the fingers and thumb of the hand of the user. If it is desired to more securely attach the applicator to the hand of the user, a wrist strap 40 may be secured to the body portion 33 having the snap fastener 41.

Although I have shown several different forms of my toilet powder applicator, the principle in each form is the same and the advantages and usefulness of the invention will readily be understood by those skilled in the art.

Some changes may be made in the construction and arrangement of my improved toilet powder applicator, without departing from the real spirit and purpose of my invention and it is my intention to cover by my claims any modified forms of structure or use of mechanical equivalents which may be reasonably included within their scope.

I claim:

1. In a device of the class described, a body member having an opening in one of its sides for holding powder, an outwardly extending peripheral flange on the marginal edge of the side having the opening, and cloth fabric secured to said body portion and extending over said face and opening.

2. In a device of the class described, a body member having a comparatively large flat surface, a cloth fabric secured around said flat surface and held and supported in normal position by said flat surface, a powder reservoir communicating with said flat surface, and a projection on said flat surface for yieldingly holding said cloth a slight distance from said flat surface so that powder may pass from said reservoir to a position between said flat surface and said cloth.

3. In a device of the class described, a body member having a comparatively large flat surface, a cloth fabric secured around said flat surface and held and supported in normal position by said flat surface, a powder reservoir communicating with said flat surface, and a forwardly extending peripheral flange on the marginal edge of said flat surface for yieldingly holding said cloth a slight distance from said flat surface so that powder may pass from said reservoir to a position between said cloth and said flat surface.

4. In a device of the class described, a body member having a comparatively large flat

surface, a cloth fabric secured around said flat surface and held and supported in normal position by said flat surface, a powder reservoir communicating with said flat surface and the back of said body member, a lid member for closing said reservoir at the back portion of said body member, and a forward-

ly extending peripheral flange on the marginal edge of said flat surface for yieldingly holding said cloth a slight distance from said flat surface so that powder may pass from said reservoir to a position between said cloth and said flat surface. 10

ANDREW W. SMITH.
